(57) **CLAIM**

The ornamental design for a display screen or portion thereof with graphical user interface, as shown and described.

DESCRIPTION

FIG. 1 is a front view of a display screen or portion thereof with graphical user interface according to a first embodiment of our claimed design; and, FIG. 2 is a front view of the display screen or portion thereof with graphical user interface according to a second embodiment of our claimed design. The evenly dashed lines, which depict portions of the graphical interface, and the unevenly dashed lines, which depict the display screen, form no part of the claimed design.
